CLAIM

The ornamental design for a sheep skin top member of an animal bed assembly, as shown and described.

DESCRIPTION

FIG. 1 is a top, front right perspective view of a first embodiment of a sheep skin top member shown according to the present design;

FIG. 2 is a bottom, front right perspective view thereof;

FIG. 3 is a front end view thereof;

FIG. 4 is a rear end view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top, front right perspective view of a second embodiment of a sheep skin top member shown according to the present design;

FIG. 10 is a bottom, front right perspective view thereof;

FIG. 11 is a front end view thereof;

FIG. 12 is a rear end view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a top, front right perspective view of a third embodiment of a sheep skin top member shown according to the present design;

FIG. 18 is a bottom, front right perspective view thereof draped over an animal bed;

FIG. 19 is a front end view thereof;

FIG. 20 is a rear end view thereof;

(Continued)

FIG. 21 is a right side elevational view thereof;
 FIG. 22 is a left side elevational view thereof;
 FIG. 23 is a top plan view thereof;
 FIG. 24 is a bottom plan view thereof draped over an animal bed;
 FIG. 25 is a top, front right perspective view of a fourth embodiment of a sheep skin top member shown according to the present design;
 FIG. 26 is a bottom, front right perspective view thereof draped over an animal bed;
 FIG. 27 is a front end view thereof;
 FIG. 28 is a rear end view thereof;
 FIG. 29 is a right side elevational view thereof;
 FIG. 30 is a left side elevational view thereof;
 FIG. 31 is a top plan view thereof; and,
 FIG. 32 is a bottom plan view thereof draped over an animal bed.

The broken line representations in the figures show unclaimed environment or boundaries. The broken line representations thus form no part of the claimed design as filed.
